ONE-PIECE GUARD RAIL

John V. Stewart, Johnstown, Pa.

Application March 31, 1933, Serial No. 663,775

6 Claims. (Cl. 238—19)

My invention relates to tracks and rails, particularly to guard rails.

Owing to the restricted space between the guard rail and the main rail with which it is associated, difficulties are presented to the fastening of the guard rail at its inner edge adjacent the main rail.

Heretofore means have been proposed to overcome this difficulty by providing extensions to underlie or underlap the main rail and thus hold the guard rail against upward or outwardly turning movement, but these means have required special and cumbersome rearrangements of the main rail mounting.

An object of my present invention is to provide a simple and effective means for securing the inner side of a guard rail to the base of a main rail without interfering with the mounting of the main rail on its rail plate and in a manner to permit the guard rail to be mounted and secured in position or be removed without altering the main rail or its mounting.

The features of the invention are illustrated in the accompanying drawings, in which

Fig. 1 is a plan view of a rail and guard rail and mounting embodying a preferred form of the invention;

Fig. 2 is a side elevation of the guard rail;

Figs. 3, 4 and 5 are vertical sections of the rail and guard rail taken on lines 3—3; 4—4 and 5—5 of Fig. 1;

Fig. 6 is an end elevation of the rail and guard rail.

In the embodiment of the invention shown in the accompanying drawings, a main rail 10 and guard rail 11 are mounted on rail plates 12 which extend beneath both rails in transverse relation thereto and which are in turn mounted on ties 13. Any suitable type of plate 12 may be employed; a plate of the general type shown in Buchholz Patent 1,640,750, granted August 30, 1927, being shown by way of example. This plate is provided with a pair of ribs 14 and 15, one at each edge of the base flange of the rail 10, and provided with retaining bolts 16 and 17 to secure clamps 18 and 19 against the upper surfaces of the rail flanges, and thus hold the rail securely in position. A similar rib 20 is provided on each plate together with a bolt 21 and clamp 22 to secure the outer flange 23 of the guard rail 11.

The guard rail 11 is provided with an upwardly inclined web 24 which is so shaped, as shown in Fig. 1, as to diverge from the rail 10 at the ends of the guard rail. This web 24 may be strengthened by vertical reinforcing ribs 25 and

26 at the inner and outer sides of the web respectively.

As shown in Fig. 5, certain of the clamps 18 may overlap the inner edge of the base flange 21 of the guard rail 11 and thus serve to hold it 5 in position. In other cases, as shown for example in Fig. 3, the clamps 18 rest at one side at the upper edge of the flange of the rail 10, and on the opposite side directly on the base plate 12. The mounting shown in Fig. 3 is illustrated in 10 Fig. 1 as used in the innermost pair of plates, and that shown in Fig. 5, as used on the plates next to this innermost pair.

To secure the guard rail against outwardly turning stresses, it is anchored to the under surface of the main rail 10 at intervals by means of projections or extensions 28 which are depressed below the level of the guard rail flanges 23 and 27 and extend sidewise to a substantial distance below the rail 10. These projections or extensions 20 28 are placed between the plates 12 and ties 13 of the trackway, and may, therefore, be readily inserted after the main rail 10 has been secured in position.

The upper surface of the projection 28 is approximately at the same level as the lower surface of the guard rail. In those cases in which a shim is used on the main rail, but not on the guard rail, as is the case in the modification shown in Figs. 3 and 5 of the drawings, the 30 guard rail is so constructed that the upper surface of extension 28 will be above the lower surface of the guard rail by a distance equal to the width of the shim. The extension will then fit tightly against the bottom surface of the rail. 35 The extension 28 is strengthened by means of a rib 29. By having the rib 29 at approximately the same position on the rail as the ribs 25 and 26, a maximum strengthening of the rail is attained.

To enable the nuts to be fastened on the bolts 16, the guard rail is provided with elongated slots 30 through which a wrench may be inserted.

Through the above arrangement, a guard rail and mounting therefor are provided which enables the rail to be readily inserted and anchored to the main rail after the latter has been secured in place and without interfering in any way with the mounting of the main rail or necessitating any changes therein.

What I claim is:

1. A rail structure comprising a main rail and a guard rail, tie plates supporting said rails, said tie plates having three ribs extending longitudinally of the direction of said rails and spaced to 55

- provide a seat for said main rail between an intermediate rib and an outer rib and to provide a seat for the guard rail between the intermediate rib and the other outer rib, clamps securing the edges of said main rail and the outer edge of said guard rail to said plates, and extensions from the inner edge of said guard rail between said plates below said main rail to secure the latter against outward overturn, said extensions comprising flat plates the upper surfaces of which are substantially on the level of the lower surface of the rail base and decreasing in width toward their ends and having downwardly depending vertical strengthening ribs extending below and united to the base of the rail and decreasing in depth toward their ends.
2. A rail structure comprising a main rail and a guard rail, tie plates supporting said rails, said tie plates having three ribs extending longitudinally of the direction of said rails and spaced to provide a seat for said main rail between an intermediate rib and an outer rib and to provide a seat for the guard rail between the intermediate rib and the other outer rib, clamps securing both edges of said rails to said plates, and extensions from the inner edge of said guard rail between said plates below said main rail to secure the latter against outward overturn, said extensions comprising flat plates the upper surfaces of which are substantially on the level of the lower surface of the rail base and decreasing in width toward their ends and having downwardly depending vertical strengthening ribs extending below and united to the base of the rail and decreasing in depth toward their ends.
3. A rail structure comprising a main rail and a guard rail, tie plates supporting said rails, said tie plates having three ribs extending longitudinally of the direction of said rails and spaced to provide a seat for said main rail between an intermediate rib and an outer rib and to provide a seat for the guard rail between the intermediate rib and the other outer rib, clamps secured to said ribs securing the edges of the said main rail and the outer edge of said guard rail to said plates, and extensions from the inner edge of said guard rail between said plates below said main rail to secure the latter against outward overturn, said extensions comprising flat plates the upper surfaces of which are substantially on the level of the lower surface of the rail base and decreasing in width toward their ends and having downwardly depending vertical strengthening ribs extending below and united to the base of the rail and decreasing in depth toward their ends.
4. A rail structure comprising a main rail and a guard rail, tie plates supporting said rails, said tie plates having three ribs extending longitudinally of the direction of said rails and spaced to provide a seat for said main rail between an intermediate rib and an outer rib and to provide a seat for the guard rail between the intermediate rib and the other outer rib, clamps securing the edges of said main rail and the outer edge of said guard rail to said plates, and extensions from the inner edge of said guard rail between said plates below said main rail to secure the latter against outward overturn, said extensions having a downwardly depending strengthening rib.

nally of the direction of said rails and spaced to provide a seat for said main rail between an intermediate rib and an outer rib and to provide a seat for the guard rail between the intermediate rib and the other outer rib, clamps securing the edges of said main rail and the outer edge of said guard rail to said plates, and extensions from the inner edge of said guard rail between said plates below said main rail to secure the latter against outward overturn, said extensions comprising flat plates the upper surfaces of which are substantially on the level of the lower surface of the rail base and decreasing in width toward their ends and having downwardly depending vertical strengthening ribs extending below and united to the base of the rail and decreasing in depth toward their ends, said guard rail having a longitudinal web inclined upwardly and toward said main rail and having sidewise extending reinforcing abutments.

5. A rail structure comprising a main rail and a guard rail, tie plates supporting said rails, said tie plates having three ribs extending longitudinally of the direction of said rails and spaced to provide a seat for said main rail between an intermediate rib and an outer rib and to provide a seat for the guard rail between the intermediate rib and the other outer rib, clamps secured to said ribs securing the edges of the said main rail and the outer edge of said guard rail to said plates, and extensions from the inner edge of said guard rail between said plates below said main rail to secure the latter against outward overturn, said extensions comprising flat plates the upper surfaces of which are substantially on the level of the lower surface of the rail base and decreasing in width toward their ends and having downwardly depending vertical strengthening ribs extending below and united to the base of the rail and decreasing in depth toward their ends, said guard rail having a vertical longitudinal web and holes through said web positioned to give access to the clamps secured to said intermediate rib.

6. A rail structure comprising a main rail and a guard rail, tie plates supporting said rails, said tie plates having three ribs extending longitudinally of the direction of said rails and spaced to provide a seat for said main rail between an intermediate rib and an outer rib and to provide a seat for the guard rail between the intermediate rib and the other outer rib, clamps securing the edges of said main rail and the outer edge of said guard rail to said plates, and extensions from the inner edge of said guard rail between said plates below said main rail to secure the latter against outward overturn, said extensions having a downwardly depending strengthening rib.

JOHN V. STEWART.
